Patented Feb. 2, 1915.

UNITED STATES PATENT OFFICE.

ALLEN RAY MOLLISON, OF ENDERLIN, NORTH DAKOTA.

VENTILATING-SCREEN.

1,127,068.

Specification of Letters Patent.

Patented Feb. 2, 1915.

Application filed May 7, 1914. Serial No. 837,092.

To all whom it may concern:

Be it known that I, ALLEN R. MOLLISON, a citizen of the United States, and a resident of Enderlin, in the county of Ransom and State of North Dakota, have invented 5 an Improvement in Ventilating-Screens, of which the following is a specification.

This invention relates to window screens, and more particularly to an improved 10 ventilating screen.

One of the principal objects of the invention is to provide an improved adjustable screen for use in sleeping rooms, hospitals, Pullman cars, and other places where the 15 admission of fresh air, without the presence of objectionable drafts, is desired.

Another object of the invention is to provide a screen of the class described, including a pair of cloth or fine wire screen 20 stretched frames, and means for securing the frames together whereby they may be adjusted relatively to each other to fit various sized windows.

A further object of the invention is to 25 provide a screen including frames covered with cloth, or fine wire mesh which will allow a steady ingress of fresh air to a room and will prevent the entrance of drafts.

Still another object is to provide a screen 30 of the class described, having adjusting means between the frames, including a bolt carried by each frame and extending through a slot in the opposite frame and into a channeled strip positioned over the 35 slot to prevent the passage of drafts therethrough, and to protect the bolt from the weather.

An additional object of the invention is 40 to provide an improved ventilating screen which will be simple, durable, efficient in operation and inexpensive to manufacture.

With these and other objects in view which will become apparent as the description proceeds, the invention resides in the 45 construction, combination and arrangement of parts hereinafter more fully described and claimed and illustrated in the accompanying drawing, in which like characters of reference indicate like parts throughout the 50 several figures, of which—

Figure 1 represents a front elevational view of a screen constructed according to my invention. Fig. 2 represents an enlarged 55 vertical transverse sectional view taken on the plane indicated by the line 2—2 of

Fig. 1. Fig. 3 represents a fragmentary horizontal sectional view taken on the plane indicated by the line 3—3 of Fig. 1, and Fig. 4 represents an enlarged perspective view of one end of one of the frames, showing the filler strip thereon.

Referring more particularly to the drawing, the screen comprises a pair of rectangular frames 5 and 6 covered with muslin or other suitable cloth which will allow the 65 percolation of air therethrough, the cloth being indicated at 7 and being secured to the outer faces of the frames by means of facing strips 8 overlying the edges 9 of the cloth, and secured by suitable brads or 70 tacks 10. The frames are arranged with their inner faces against each other, and in order to connect them together so that they may be adjusted each longitudinally of the other, the top rail of one frame and the bottom rail of the other, are provided with elongated slots 11 extending substantially 75 throughout the length of the frames, and in the slots are adapted to travel bolts 12 carried by the frames, a bolt being carried by 80 each frame at the inner end of the rail opposite the rail provided with the slot as clearly indicated, said bolts being oppositely disposed and extending loosely through the slots and being headed at their outer ends 85 as at 13 to prevent lateral displacement of one frame relative to the other.

Secured to the outer face of each frame and disposed over the slot provided in the frame is a metallic strip 14 channeled 90 throughout its length as at 15, the channel being of substantially the same curvature as the head of the bolt which rides in the slot, and said metal strips are adapted to prevent the passage of currents of air 95 through the slots and also shield the bolts from the weather, so that the danger of their becoming rusted will be minimized, the strips may be secured as indicated by 100 brads or other fastening means 16.

As indicated in Figs. 2 and 3 there necessarily occurs between the strips of cloth covering the screens, a considerable space indicated at 17, and when the screens are pulled out as indicated in Fig. 1 it would 105 be possible for a current of air to enter the room between the sheets of cloth, were not provision made to block up this space, and in order to do this I provide one of the end bars 18 of one of the frames, with 110

a filler strip of wood or other suitable material 19 which is of a thickness sufficient to occupy the distance between the end rail and the opposite sheet of cloth, so that the 5 filler strip is in contact throughout its length with the cloth, and prevents the creation of drafts between the cloth sheets, as will be readily understood. The strip is of a length equal to the distance apart of 10 the longitudinal bars of the frame, so that at its ends it engages the inner edges of the longitudinal bars of the opposite frame and hence the strip aids the bolts in guiding the frames as they are adjusted.

15 Finely woven wire cloth or other filtering fabric may be used with the frame, and will serve the same purposes as the muslin or similar cloth.

Ventilating screens constructed according 20 to my invention are adapted to be positioned in the window casings of sleeping apartments or other buildings where a supply of fresh air is wanted, and since the screens are adjustable they will fit various sized window 25 casings, and by their construction it is evident that while they allow a supply of fresh air to percolate through the cloth coverings they absolutely prevent the entrance of drafts, and they also prevent the entrance of 30 rain or snow into the apartment.

Although I have described the preferred embodiment of my invention, I may desire to make such changes in the construction, combination and arrangement of parts 35 thereof as do not depart from the spirit of the invention and the scope of the appended claims.

Copies of this patent may be obtained for five cents each, by addressing the "Commissioner of Patents
Washington, D. C."

I claim:

1. A ventilating screen comprising a pair of frames adjustable with relation to each other, each of the frames provided with an elongated slot extending substantially the length of one of the longitudinal members of the frame, a single bolt carried by each frame adjacent one corner thereof and extending through the adjacent slot in the opposite frame, said slots occurring in the opposite longitudinal members of the assembled screen, covering strips for the slots adapted to prevent entrance of drafts there-through and adapted to protect the bolts, sheets secured over said frames, and adapted to allow the percolation of air there-through, and means for preventing entrance of drafts through the sheets. 50

2. A ventilating screen comprising a pair of frames adjustable with relation to each other, each frame having a slot extending approximately the entire length of one longitudinal member thereof and having a bolt 60 carried by the other longitudinal member at one corner of the frame, said frame being assembled in opposite relation so that the bolt of one frame extends through the slot of the opposite frame, means for covering the slots to protect the bolts and prevent entrance of drafts through the slots, screening sheets secured to the frames, and means for preventing entrance of drafts through the sheets. 65

ALLEN RAY MOLLISON.
